UNITED STATES PATENT OFFICE.

JOHN ANTHONY, OF ATTLEBORO, MASSACHUSETTS.

ORNAMENTAL CHAIN.

Application filed April 18, 1927. Serial No. 184,600.

My invention relates to ornamental chains adapted for use in necklaces, bracelets, girdles and other articles for personal adornment.

The essential objects of my invention are to produce a chain having the appearance of intertwined lengths such as rope chain; to produce such a chain by the use of a single piece of material only; to avoid the use of solder; and to prevent the chain springing asunder when no retaining means are applied to the chain ends, and inexpensiveness.

To the above ends essentially my invention consists in such parts and combinations of parts, and in such steps and in such successions of steps as fall within the scope of the appended claims.

In the accompanying drawings which form a part of this specification

Figure 1 is a plan view of a wire fabric blank from which my chain is ultimately bent,

Figures 2 and 3, a front elevation and an end elevation respectively of the chain after the longitudinal bending of the same,

Figure 4, a side elevation of the chain partially twisted,

Figure 5, a section on line 5—5 of Figure 4, and

Figure 6, a side elevation of the completed chain.

Like reference characters indicate like parts throughout the views.

In embodying my invention an oblong strip or blank 8 of flexible metallic or wire fabric of any usual or preferred construction is used. Such a strip is shown in Figure 1.

Manually or by tools the strip 8 has its lateral edges 9 and 10 bent or rolled in directions oppositely to each other, bringing said edges adjacent to or into contact with the medial portion 11 of the blank at opposite sides of the latter, thus forming two parallel rolls or cylinders 12 longitudinally disposed as shown in Figures 2 and 3.

Next by manual manipulation or by pulling the same through a draw plate or otherwise the member 8 is twisted so that the portions 12 mutually overlap each other in a series of spiral loops 13. In Figure 4 the strip is shown during the twisting operation. In Figure 6 the completed chain is shown.

It should be noted that the chain thus described is flexible and that loops 13 have no tendency to separate from their interengaged torsional positions as would be the case if the tubes 12 or loops 13 were nonintegral with each other. For this reason also fastening means for the chain ends are unnecessary.

I claim:

1. In an ornamental chain of the type set forth, a flexible wire mesh body substantially 65 shaped in cross section comprising interengaging laterally connected hollow spiral loops interengaged in torsional positions and closely adhering to each other.

2. In an ornamental chain of the type set forth, a flexible wire mesh body comprising laterally connected rolls disposed in continuous hollow spiral interengaged loops, interengaged in torsional positions and closely adhering to each other.

3. An ornamental metal stock for a flexible chain formed of a single piece of flexible wire mesh bent at its lateral margins to form opposed rolls and twisted to form a continuous member of continuous hollow spiral loops laterally interengaged with the edges of the 80 piece of mesh concealed and interengaged in torsional positions and closely adhering to each other, the whole simulating a rope chain.

In testimony whereof I have affixed my 85 signature.

JOHN ANTHONY.
